US00D842644S

(12) **United States Design Patent** (10) **Patent No.:** **US D842,644 S**
Kettavong et al. (45) **Date of Patent:** **** Mar. 12, 2019**

(54) **BLENDING SYSTEM**(71) Applicant: **Vita-Mix Management Corporation**, Olmsted Township, OH (US)(72) Inventors: **Phonesacksih Guy Kettavong**, Kent, OH (US); **Jack Warren Gee, II**, Willoughby, OH (US); **Kolman Juhasz**, Parma, OH (US); **Eugene J. Kozlowski**, Medina, OH (US); **David A. Kanning**, Valley City, OH (US); **Michael Patrick Arnett**, Columbia Station, OH (US); **Richard Joseph Lash**, Avon Lake, OH (US)(73) Assignee: **Vita-Mix Management Corporation**, Olmsted Township, OH (US)(***) Term: **15 Years**(21) Appl. No.: **29/630,478**(22) Filed: **Dec. 21, 2017****Related U.S. Application Data**

(62) Division of application No. 29/584,798, filed on Nov. 17, 2016, now Pat. No. Des. 807,118, which is a division of application No. 29/485,013, filed on Mar. 14, 2014, now Pat. No. Des. 771,999.

CLAIM

The ornamental design of a blending system, as shown and described.

DESCRIPTION

FIG. 1 is a perspective view of a blending system showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the figures are included for the purpose of illustrating portions of a blending system and form no part of the claimed design.
